FOLDING STEREOSCOPIC VIEWER

Robert C. Beck, Los Angeles, Calif.

Application March 16, 1953, Serial No. 24,055

Term of patent 7 years

(Cl. D61—1)

To all whom it may concern:

Be it known that I, Robert C. Beck, a citizen of the United States of America, residing at Los Angeles, in the county of Los Angeles, State of California, have invented a new, original, and ornamental Design for a Folding Stereoscopic Viewer, of which the following is a specification, reference being had to the accompanying drawing, forming a part hereof.

Figure 1 is a front perspective view of a folding stereoscopic viewer, showing my new design;

Figure 2 is a top plan view thereof;

Figure 3 is an end elevational view thereof;

Figure 4 is a rear elevational view thereof;

Figure 5 is an elevational view thereof to a smaller scale of the rear of the front wall, taken on the line 5—5 of Figure 3;

Figure 6 is a bottom plan view thereof; and

Figure 7 is an end elevational view thereof showing the viewer in folded position.

I claim:

The ornamental design for a folding stereoscopic viewer, as shown.

ROBERT C. BECK.
